UNITED STATES PATENT OFFICE.

WILFRID HEUSSER, OF SALT LAKE CITY, UTAH.

MECHANICAL PAN-EXTRACTOR FOR BALANCES.

1,316,890.

Specification of Letters Patent. Patented Sept. 23, 1919.

Application filed November 3, 1915. Serial No. 59,465.

To all whom it may concern:

Be it known that I, WILFRID HEUSSER, a citizen of Switzerland, and a resident of Salt Lake City, in the county of Salt Lake 5 and State of Utah, have invented a new and useful Mechanical Pan-Extractor for Balances, of which the following, together with the accompanying drawings, forms a full, clear, and exact specification.

10 My invention relates to a mechanical pan extractor for balances, the objects of which are similar to those enumerated in my application for U. S. Patent filed July 6th, 1915, Serial No. 38,287. Specifically these objects 15 are:

1st. To make it unnecessary, during the operations of weighing, to open the door which usually covers the entire front of the balance-case.

20 2nd. To provide small closable openings in the door or walls of the usual balance-case through which the balance pans may be removed from the inside of the balance-case and be brought to points outside thereof 25 where weights may be readily placed in, weights changed, or objects to be weighed, be placed in the pans without disturbing the equilibrium of the balance.

30 3rd. To provide mechanical means operated from the outside of the balance-case, for lifting the pans out of the hangers, bringing them to positions outside the balance-case, and to return the pans to their normal positions in the hangers.

35 4th. To prevent the excessive rush of air which is occasioned every time the door of the usual balance-case is opened and which seriously disturbs the equilibrium of the balance.

40 5th. To eliminate almost entirely the entrance of dust into the balance-case from the outside air.

In the present invention these objects are accomplished by means of a curved horizontal arm projecting rigidly from a vertical, pivoted post which is so arranged that it may be raised and lowered within predetermined limits and which furthermore may be rotated to a predetermined extent 50 when it is in its uppermost position.

The pivoted post is so placed that the curved arm, which is adapted to support a balance pan on its free extremity, may be caused to lift the balance pan out of its hanger and to bring it forward through a 55 small, closable opening in the door, or in the

walls of the balance-case. The device is operated from the outside of the balance-case and its motion is limited in such a way that the curved arm can never come into contact 60 with the delicate parts of the balance through carelessness on the part of the operator.

The features on which protection is desired are summarized in the appended 65 claims.

In the drawings:

Figure 1 represents a plan view partly in section, of a portion of an ordinary balance showing my invention in one of its forms, 70 applied thereto;

Fig. 2, a front elevation, partly in section on the line 2-2 in Fig. 1, and Fig. 3, a minor detail in section on the line 3-3 in Fig. 2; 75

Fig. 4, an elevation of minor parts, viewed in the direction of the arrow 4 in Fig. 2.

Fig. 5 is identical with Fig. 1, but the parts of my invention are shown in an alternate position. 80

Fig. 6 represents a section taken on the line 6-6 in Fig. 5.

Figs. 7 and 8 represent elevations in different alternate positions of certain parts 85 shown in Fig. 6, and

Figs. 9 and 10, sections, taken on the line 9-9 in Fig. 7, and the line 10-10 in Fig. 8, respectively.

Fig. 11 represents a plan view of a portion 90 of an ordinary balance and shows my invention in a modified form applied thereto.

Fig. 12 represents a front elevation, partly in section on the line 12-12 in Fig. 11, and 95

Fig. 13, a section taken on the line 13-13 in Fig. 12.

Throughout the different figures similar parts are designated by similar numerals.

Referring to the drawings, the preferred 100 form of my invention as illustrated by Figs. 1 to 12, will be described first. In these figures, 20, represents the base of an ordinary balance near one corner of which, and inside the walls 21 of the balance-case, is located a vertical sleeve 22 having the laterally projecting concentric flange 23 which may be fastened to the base 20 by the screws 24. One end of the sleeve 22 extends below the flange 23 and through an opening in 105 the base 20. The upper portion of the sleeve 22 has an inverted L-shaped open-

ing, as shown in Figs. 6, 7 and 8, cut through its wall, the purpose of which will presently be explained. A bushing 25 is journaled in the core of the sleeve 22 and 5 is held therein by the integral collar 26 near its lower end and by the removable set collar 27 at its upper end. The bushing 25 has an opening extending longitudinally through it which is adapted to receive 10 the post 28 and to allow it to be moved up and down therein. The post 28 is preferably of rectangular cross section and at its upper end carries the rigidly fastened curved arm 29 while at its lower end it carries 15 the nut 30 which forms a stop for limiting the upward travel of the post 28. The bushing 25 at, and to one side of its lower extremity, has the integral circular housing 31 which terminates in the extended 20 concentric bearing sleeve 32. Journaled in the bearing sleeve 32 is a shaft 33 which carries a rigidly mounted pinion 34 inclosed by the housing 31. The shaft 33 extends somewhat beyond the side of the base 20 25 as shown in Figs. 1 and 2, and at its outer end has the rigidly mounted knob 35.

The open end of the housing 31 may be closed by a head 36 shown in Figs. 3 and 6 and this head may be bored to form a bearing 30 for one end of the shaft 33. The head 36 may be held in the housing 31 by a set screw 37. The lower portion of the post 28 has a suitable number of gear teeth 35 cut in one of its sides which form a rack adapted to mesh with the pinion 34 as shown in Fig. 4. At 38 (Figs. 6 to 10) is a pin which is rigidly fastened in the post 28 and which projects therefrom through a slot 39 in the bushing 25 and through the 40 inverted L-shaped opening in the sleeve 22. The curved arm 29 at its free end terminates in a ring 40 from the inside circumference of which project three prongs 41 for supporting the balance pan 49. In 45 front, the ring 40 has the pilot finger 42, the purpose of which will presently be made clear.

In the door 43 of the balance-case is a 50 suitably located opening, normally closed by the crystal 44 which may be secured in a hinged metal frame 45 and which may be yieldingly held in the closed position shown in Fig. 1, by the spring 46. The normal position of the present device relatively to 55 the pan hanger 47 with its three-pronged, pan-supporting griff 48 as constructed in the balances of my regular manufacture, is shown in Figs. 1, 2 and 4 where the ring portion 40 of the curved arm 29 encircles the staff of the griff 48 at a point about midway between the pan 49 and the bottom bar of the hanger 47, when the post 28 is at the lowermost point of its travel.

In using this device, supposing it to be 60 in the normal position, the operator first

turns the knob 35 in the clockwise direction, causing the pinion 34 to elevate the post 28 with its curved arm 29, to the position shown by dotted lines in Fig. 2, carrying with it the pan 49 which will have 70 become engaged by the lugs 41 and be lifted out of the griff 48 to its new position. Now, by pushing the knob 35 backward in the direction indicated by the arrow in Fig. 1 the movable parts of the device will come 75 into the position shown in Figs. 5 and 6, the pilot finger 42 having meanwhile been caused to bear against the inner surface of the crystal 44, and to push it open against the pressure of the spring 46 to the position shown. Any weights or other objects 80 may now be taken out of, or be placed in, the pan 49 and the same may be returned to its normal position in the hanger 47.

The movements of the post 28 are limited 85 by the pin 38 which is shown in its lowermost position in Fig. 7. This position of the pin 38 is only possible when the slot 39 in the movable bushing 25 registers with the depending portion of the L-shaped slot in 90 the stationary sleeve 22 as shown in Figs. 7 and 9, and in this position of the pin 38, the curved arm 29 is in the position shown in Fig. 1, having its ring portion 40 exactly concentric with the pan 49. From its lowermost position, the pin 38 may move only in the upward direction until the post 28 is stopped by the contact of the nut 30 against the bottom face of the bushing 25, when the pin 38 just clears the abutment 50 and allows 95 the rotation of the bushing 25; the pin 38 being simultaneously moved across the abutment 50 until the position shown in Figs. 8 and 10 is reached, the curved arm 29 and pan 49 at this time occupying the position shown in Fig. 5.

It will be noticed that in Figs. 2 and 6 some of the movable parts of my device are not projected in the true position which they occupy in Figs. 1 and 5 respectively, but that 100 for convenience in drawing, these parts are shown in the position occupied when the shaft 33 is parallel to the front 51 of the base 20.

In the alternate construction of my device 115 illustrated in Figs. 11, 12 and 13, the balance base 20^a has rigidly mounted on it, the sleeve 52, in which is formed the vertical slot 53 and the horizontal abutment 54. A rod 55 having the curved arm 29^a fixed thereon, is journaled in the sleeve 52, at the same time being adapted to slide up and down therein; the vertical movement of the rod 55 is limited by the hub 56 and by the nut 57, and the rotation of the rod 55 is limited by 120 the projecting pin 58. The upper part of the rod 55 extends through the top of the balance case and at its end has the fixed knob 59. Just below the knob 59, the rod 55 may be journaled in the flanges 60 and 61. 125 130

In use, the knob 59 is grasped by the hand of the operator and is pulled up into the position indicated by the dotted lines in Fig. 12, this action causing the balance pan 49^a to be lifted out of its hanger in the same manner as previously explained and by turning the knob 59 (Fig. 11) in the direction of the arrow, the pan may be brought to the outside of the balance case in a manner similar to that illustrated in Fig. 5.

Having fully described my invention, what I claim is:—

1. In a mechanical pan extractor for balances, the combination with a suitably supported guide, of a post rotatably and reciprocatively mounted therein, the guide having means for limiting the travel of the post to a certain predetermined pathway in such a manner that no rotation can take place during reciprocation and conversely no reciprocation during rotation; a suitably formed arm mounted on the said post, the said arm being adapted to carry a pan, and means for moving the said post through its predetermined pathway.

2. In a mechanical pan extractor for balances, the combination with a depressible post, of a rotatably supported bushing therefor, means for elevating and depressing the said post, a suitably shaped pan-supporting arm mounted on the said post, and mutually coöperating stops and guides for controlling the movements of the said post, thereby confining the travel of the said pan-supporting arm to an exact, predetermined path.

3. In combination with a balance structure, a pivoted post located within the structure; means, controlled from the exterior of the said structure for longitudinally elevating and depressing the said post in its bearings; means, mounted on the said post, for carrying a balance pan, and suitably disposed guides and stops for limiting the movements of the said pan-carrying means to an exact predetermined pathway.

4. In combination with a balance structure; a pivot-post, adapted to be longitudinally reciprocated in its bearings, located within the said structure; a pan-carrier rigidly mounted on the said post; means operated from the exterior of the said structure for reciprocating and rotating the said post; an automatically-closing shutter in the said structure, so located that it may be opened by being contacted by the said pan-carrier; and suitably disposed guides and stops, for controlling the movements of the said post, thereby limiting the travel of the said pan-carrier, first, to a straight line of predetermined length along the longitudinal axis of the said post, and second, upon completion of the straight-line travel, to a rotary travel of a predetermined fraction of one revolution around the axis of the said post, the

order of the travels being alternately reversed, for the purpose specified.

5. In a mechanical pan extractor for balances, the combination with a balance structure having a base, of a sleeve rigidly mounted on the base, a bushing journaled in the said sleeve; a post, having a rack portion, slidably disposed in the said bushing; a suitably journaled shaft with a pinion engaging the said rack portion, and a suitably formed pan carrier mounted on the said post for the purpose specified.

6. In a mechanical pan extractor for balances, the combination with a balance structure having a base and a casing, of a sleeve suitably mounted on the base; a bushing rotatably held in the said sleeve; a post having a rack portion, slidably disposed in the said bushing; a suitably journaled shaft with a pinion engaging the said rack portion; a suitable pan-carrier mounted on the said post, and an automatically-closing shutter in the said casing adapted to be opened by the movement of the said pan-carrier for the purpose specified.

7. In a mechanical pan extractor for balances, the combination with a balance structure having a base and a casing; of a sleeve suitably mounted on the base, inside the said casing; a bushing rotatably held in the said sleeve; a post having a rack-portion, slidably disposed in the said bushing; a suitably journaled shaft with a pinion engaging the said rack-portion; a suitable pan-carrier mounted on the said post; an automatically-closing shutter in the said casing adapted to allow the egress therefrom of a portion of the said pan carrier, and suitably disposed guides and stops for controlling the movements of the said post, thereby confining the travel of the said pan-carrier to a certain predetermined course for the purpose specified.

8. In a mechanical pan extractor, the combination with a balance structure having a case, a pan hanger and a pan; of a sleeve suitably mounted in the said structure; a bushing held in the said sleeve and having a limited rotative motion therein; a post held in the said bushing and having a limited longitudinal sliding motion therein; and an arm mounted on the said post for engaging the said pan in a manner that will allow it to be lifted out of the said hanger and to be brought to a point outside the said casing, all for the purpose specified.

9. In a mechanical pan extractor, the combination with a balance structure having a case, a pan hanger and a pan, of a sleeve having an inverted L-shaped opening therein, the sleeve being suitably mounted in the said structure; a bushing concentrically movable in the said sleeve and having a slot registering with the said L-shaped opening;

a post, slidably and non-rotatably held in the said bushing, the said post having a projecting pin extending through the said L-shaped opening and the said slot; and a 5 suitable arm mounted on the said post for allowing the pan to be lifted out of the pan hanger and to be brought to a point outside the case.

10. In a mechanical pan extractor, the 10 combination with a balance structure, of a stationary sleeve having an L-shaped opening therein; a slotted bushing journaled in the said sleeve; a slidable post non-rotatably mounted in the said bushing; a pin rigidly 15 projecting from the said post and extending through both the said L-shaped opening

and the slot in the said bushing; a suitable pan-carrying arm mounted on the said post; an automatically closing shutter suitably located in the said structure and adapted to 20 be opened by the movement of the said arm; and means for imparting a longitudinal motion and a rotary motion to the said post from the exterior of the said balance structure as specified.

25

In testimony that I claim this invention as my own I have signed my name hereto in the presence of two subscribing witnesses.

WILFRID HEUSSER.
